UNITED STATES PATENT OFFICE.

DONALD MOIR AND HUGH BUCHANAN, OF ROSARIO DE SANTA FÉ, ARGENTINA.

MANUFACTURE, CENTRIFUGALLY, OF HOLLOW ARTICLES.

1,223,602.

Specification of Letters Patent. Patented Apr. 24, 1917.

Application filed February 12, 1916. Serial No. 77,972.

To all whom it may concern:

Be it known that we, DONALD Moir and HUGH BUCHANAN, subjects of the King of Great Britain and Ireland, residing at Rosario de Santa Fé, Argentina, have invented Improvements Relating to the Manufacture, Centrifugally, of Hollow Articles, of which the following is a specification.

This invention relates to a process of manufacturing articles, centrifugally, such for examples as concrete pipes and other hollow ware having smooth internal surfaces.

In such processes proposals have been made according to which material, such for example as cement or lime concrete or other suitable agglomerate intended to be subjected to centrifugal action, is to be received by a configuring member confined within outer inclosing means designed to resist the bursting stresses to which the inner configuring member is to be subject, such configuring member being designed to be removed as soon as the material has been sufficiently acted upon by centrifugal force.

The present invention which is applicable, whether the smooth internal surfaces are to be the final stage of articles made throughout by a centrifugal method of production, or the linings, produced centrifugally, of articles made in any other way, consists in a process of the kind specified whereby the material to be formed into a surfaced article is introduced into an inner configuring member, which may be one of a number having a variety of forms differing widely from that of the outer supporting means, and centrifugally consolidated therein after which superfluous material is removed in adjustable manner from the inner surface simultaneously along its whole length and diverted into a collector, the formed article being then removed together with the inner configuring member.

It will be understood that the inner mold will be shaped to suit the exterior formation of the pipe, column or the like and also that the invention can be usefully adapted to the lining of articles such as pipes with material for purposes such as the strengthening, waterproofing or finishing of the same.

In the accompanying drawings, Figure 1 is a longitudinal and Fig. 2 a transverse section showing one form of centrifugal mold arrangement suitable for carrying out the process as used for the manufacture of a reinforced pipe cylindrical throughout, both

externally and internally. Figs. 3 and 4 are similar views of a modified arrangement for use in the manufacture of a spigot and faucet pipe. Figs. 5 to 8 are diagrammatic views illustrating the manner of adjustably removing surface material simultaneously throughout the length of the article and collecting it, and Fig. 9 is a view of the general arrangement of plant adapted for the purpose of the invention.

Referring first to Figs. 1 and 2, *a* is the bearing of a horizontal driving shaft *b* provided with a boss or head *c* that is furnished with a collar or flange *d*. To this collar *d* is bolted one half *e* of a cylindrical casing that has flanges *f* enabling it to be securely bolted to the flanges *g* of a companion casing part *h*. The inner mold comprises a sheet *i* of metal bent into cylindrical form having scarfed overlapping edges at *j*. This mold is supported within and from the casing parts *e*, *h* by rings *k* intermediate of its length and by ring formers *m* at the ends. The rings *k* as can be clearly seen in Fig. 2 are each made in halves interengaging and connected together by pins *n*. The end formers *m* are made in separable parts in the same way as the rings *k*. *o* represents a layer of suitable agglomerate which is first acted upon centrifugally, *p* represents a metal reinforcement which is next added and *r* represents the subsequent layer of agglomerate centrifugally treated. The left hand end former *m* is of a radial depth sufficient to produce an end wall accommodating both layers of agglomerate but in order to permit of the entry of the reinforcement *p* into the mold the right hand end former *m* is radially of lesser depth, having combined therewith a supplemental ring *m'* which is fixed to the former *m* after the reinforcement *p* has been introduced and before the inner layer *r* of agglomerate is formed.

In Figs. 3 and 4 the cylindrical mold *i* of Figs. 1 and 2 is replaced by a mold *i'* which is shouldered at *i''* to form a socket, the rings *k'* and end formers *m'', m''* being altered in dimensions to those employed in Figs. 1 and 2. In other respects the apparatus is the same.

Fig. 9 shows means according to Figs. 1 and 2 or to Figs. 3 and 4 mounted in relation to a distributing trough *s*, the casing *e*, *h* being supported at one end by a roller *t*. The trough *s* is carried upon a shaft *u* by eccentrics *v* (Figs. 5 to 8) and is provided

with a scraping edge w , a handled bolt x being shown as provided to engage one of the eccentrics v whereby the trough can be clamped in different angular positions relatively to the shaft u . This shaft u is fitted with a handle y and is revoluble in a sliding bearing z , the arrangement being such that the shaft and trough can be advanced longitudinally into the positions indicated in dot and dash lines where the end s^1 of the shaft s enters a housing b^1 in the end of the shaft b . Normally the trough s is clamped to the shaft u so that it can be freely moved longitudinally into the inner mold, as exemplified in Fig. 5, after which it can be turned by the handle y into a position (see Fig. 6) to enable its contents to be discharged. Afterward the angular position of the trough s in relation to the shaft u can be altered, as exemplified in Figs. 7 and 8, to vary the distance of the dressing edge w from the center of rotation which distance is a maximum in Fig. 8.

What we claim is:—

- 25 1. In a process of the kind described for producing hollow articles the step of centrifugally smoothing the internal surface by removing and collecting superfluous material therefrom along its whole length simultaneously.
- 30 2. The process of manufacturing hollow articles centrifugally which consists in assembling parts of a configuring member within rotary inclosing means adapted to resist centrifugal bursting stresses, introducing material to be centrifugally acted upon into the configuring member, consolidating the same centrifugally, removing and collecting superfluous material from the internal surface of the article along its whole length simultaneously, removing the configuring member with its contents as soon as

sufficiently set to permit thereof, and allowing the contents to set completely while remaining in the configuring member.

3. The process of manufacturing hollow articles of reinforced agglomerate which consists in centrifugally consolidating a layer of agglomerate until partially set, introducing the reinforcement, following the introduction of the reinforcement by further agglomerate and centrifugally consolidating the added agglomerate upon and around the reinforcement.

4. The process of manufacturing hollow articles of reinforced agglomerate which consists in introducing agglomerate into a rotary configuring member, dressing such agglomerate interiorly to produce a layer of predetermined thickness, introducing the reinforcement, following the introduction of the reinforcement by further agglomerate and centrifugally consolidating the added agglomerate upon and around the reinforcement.

5. The process of manufacturing hollow articles of reinforced agglomerate which consists in introducing agglomerate into a rotary configuring member, dressing such agglomerate interiorly to produce a layer of predetermined thickness, introducing the reinforcement, following the introduction of the reinforcement by further agglomerate and dressing such added agglomerate interiorly to produce a second layer of predetermined thickness.

Signed at Rosario de Santa Fé, Argentina, this nineteenth day of January, 1916.

DONALD MOIR.
HUGH BUCHANAN.
